FLUID TREATMENT

William Kwo-Wei Chen and Milton Sheldon Mintz, Stamford, Conn., assignors to The American Machine and Foundry Company, a corporation of New Jersey

Filed July 20, 1960, Ser. No. 44,117

1 Claim. (Cl. 204—180)

This invention relates in general to multiple chamber fluid treatment devices, and, more particularly, to the acidification of electrodialysis stacks.

In the treatment of natural brines and other solutions by electrodialysis, the base produced at the cathode and at polarized interfaces between the surface of a membrane and the solution causes troublesome precipitation if some means is not provided to counteract it. Methods have been proposed which utilize the acid produced at the anode to counteract the formation of a base elsewhere in the stack. Since the quantity of acid produced electrodialitically at the anode can never exceed the quantity of the base produced within the stack, these procedures provide no safety factor and slight changes in the brine or solution characteristics of the fluid being treated may readily upset the delicate electrochemical balance. For this reason, it has been a more common practice to add acid from an external source to the electrodialysis stack. The major objection to this latter procedure is the relatively high cost of the equipment required for introducing acid at the proper rate and pressure.

It is, therefore, an object of this invention to provide a less costly method for the introduction of acid into an electrodialysis stack.

It is an object of this invention to provide a process of dispensing anions into the concentrating stream of an electrodialysis stack in which the process comprises the steps of maintaining in a cathode compartment a solid material, comprising acid anions (which are liberated therefrom when in contact with water) selected from solid acids and acid salts, in substantial equilibrium with a saturated aqueous solution of said solid material and diffusing said anions under electrical potential through an anion selective permeable membrane into an adjacent concentrating stream in an electrodialysis stack, whereby said solid material is depleted in the operation of said stack.

Another object of this invention is to provide an electrodialysis stack which can be operated for longer periods of time without requiring service due to precipitation within the stack.

A further object of this invention is to provide a less costly electrodialysis stack which can operate for longer periods unattended.

Many other objects, advantages and features of invention reside in the particular construction, combination and arrangement of parts involved in the embodiment of the invention and its practice as will be understood from the following description and accompanying drawing wherein:

FIG. 1 is a perspective view of an electrodialysis stack;

FIG. 2 is a vertical longitudinal section through the electrodialysis stack;

FIG. 3 is a perspective view of a fragment of one end of a gasket and an adjacent membrane; and

FIG. 4 is an exploded perspective view of the elements forming the electrodialysis stack.

Referring to the drawing in detail, FIGS. 1 and 2 show an assembled electrodialysis stack, generally designated by the numeral 29. The stack 29 is clamped between two end plates 30 and 31, which may be steel or other rigid material, by tightening the bolts 32 and drawing the end plates together. Heavier blocks of electrical insulating material 33 and 34 may be disposed inside the end plates

2

30 and 31 so that the bolts 32 are disposed beyond the center of the stack 29 and electrically insulated from it. The end plate 30 and block 33 have the electrode chamber vent pipe 35 fixed into them. The end plate 30 also receives the intake pipes 39 and 40. In a like manner, the end plate 31 receives the product and concentrate pipes 41 and 42 and the electrode chamber vent pipe 37. Referring now to FIG. 4, these pipes 35, 37, 39, 40, 41 and 42 lead to fluid flow apertures 64, 74, 61, 62, 70 and 71, respectively, which are formed in the elements comprising the stack 29. These fluid flow apertures in the stack elements form manifold passages within the stack 29.

Referring now to FIG. 3, a gasket 50 is an elongated rectangle in its external shape with a central rectangular cutout portion 52. Pairs of fluid flow apertures 45 and 46 at each end of the gasket 50 form manifold passages. Communicating from one of these fluid flow apertures 45 or 46 to the cutout chamber 52 are the small passages 47. Thus each end of the gasket 50 contains small passages 47 communicating with oppositely disposed fluid flow apertures to form hydraulic connections. A membrane 48 lies next to each side of each gasket 50. The membrane 48 contains manifold apertures corresponding to those formed in the gaskets 59. Within the central cutout portion in each gasket 50 there may be placed a screen spacer element 57.

FIGS. 2 and 4 show the arranged elements of an electrodialysis stack embodying this invention. A steel plate 30 or other reinforcement member, a plastic block 33, and an insulating sheet 65 contain the two fluid intake aperture 61 and 62 and also the electrode chamber vent aperture 64. Below the insulating sheet 65 lies the gasket 66 which is considerably thicker than the cell forming gaskets 50 so that its central opening 63 will provide a large electrode chamber. There are no internal passages formed within the gasket 66 communicating with the manifold apertures 61 and 62 which it has formed in one end. The electrode chamber 63 contains the electrode 67 which may be of platinum foil or other suitable material. An electrical connection 68 extends from this electrode to be connected to a suitable current source. The connection 68 may also be seen in FIG. 1.

After the gasket 66, there is placed a sheet 69 of a porous non-woven material which is sufficiently porous to allow either anions or cations to pass while it resists the attack of chlorine or other degradation agents generated at an electrode. This sheet 69 may be made of any porous, relatively inert material.

Following the sheet 69 there are placed a number of layers, each consisting of an anion permeable membrane 48A, a gasket 50A, a cation permeable membrane 48K, and another gasket 50B. It is to be noted that the gaskets 50A and 50B are identical except that the gasket 50B is the same as gasket 50A in the inverted position. Thus fluid may flow from the intake manifolds formed by the aligned fluid flow apertures 61 and 62 into alternate chambers 52C or 52D. In a like manner, fluid flows from these alternate chambers designated 52C or 52D into either a manifold formed by the fluid flow apertures 70 or a manifold formed by the fluid flow apertures 71.

As long a series of cells may be built up in this manner as desired by stacking up the alternate layers of gaskets 50A and 50B with the interspersed membranes 48A and 48K. At the other end of the stack, the lower end as shown in FIG. 4, there follows in reverse order another porous sheet 69 and another gasket 66 which contains a second electrode 72. Another insulating sheet 65, another plastic block 34 and another plate 31 follow, each containing the fluid flow apertures 70 and 71 and also the electrode chamber vent aperture 74.

Referring now to FIGS. 1, 2 and 4, this invention operates in the following manner. Fluid to be treated flows into the stack through pipes 39 and 40 to pass through the fluid flow apertures 61 and 62. That fluid which passes through the fluid flow apertures 61 passes through the central cutout portions 52C of the alternate gaskets 50A. The fluid which passes through the fluid flow apertures 62 would, in a like manner, pass through the central cutout portions 52D of the alternate gaskets 50B. If the membranes 48A were anion permeable membranes and the membranes 48K were cation permeable membranes, and if the electrodes 67 and 72 were connected to a direct current source so that the electrode 67 was a cathode and the electrode 72 was an anode, concentrating cells would be formed within the cutout portions 52C and diluting cells would be formed within the cutout portions 52D. Thus a dilute or product stream would flow from the stack through the fluid flow apertures 70 while a concentrate stream flowed from the stack through the fluid flow apertures 71.

Referring now to FIG. 2, an anion permeable membrane 48A is placed adjacent to each electrode compartment. The enlarged electrode compartments 63 are each packed with a cake 25 of a solid acid salt, for example, in a stagnant acid filled volume. One such acid salt which may be used is sodium bisulfate. Organic acids may also be used such as oxalic or citric. Meta phosphoric acid also works. The acid salt or solid acid may be packed into cakes as shown, it may be packed loosely into the electrode cells, or liquid solutions of an acid may be used. The invention includes use of a reserve acid supply, preferably packed into the electrode chamber.

As shown in FIG. 2, the electrode compartments or cells 63 are vented to the atmosphere by the pipes 35 and 37. The upward extensions 20 and 21 of these pipes 35 and 37 terminate in the closures 22. The closures 22 each have a cover 23 held over them by a hinge 24. Thus the covers 23 may be swung aside to introduce fluid into the electrode chambers through a suitable filtering material 26 which is placed within the closures 22. The lids 23 contain the small vent apertures 27 which allow gases generated at the electrodes to escape into the atmosphere.

When the electrode 67 functions as a cathode, fluid within this cathode chamber is a saturated solution of the acid salt with which the cathode compartment is packed. Therefore, any base produced at the cathode is immediately counteracted by the solution. Since an anion permeable membrane 48A is adjacent to each electrode compartment, there is no electroendosmotic water transfer into the cathode compartment. Water transfer by electroendosmosis is directed out of the cathode compartment, but an equilibrium is maintained by normal osmosis which results in water transfer into the cell by virtue of its high acid concentration.

If, as shown in FIG. 2, the electrode compartment on the right was not packed with an acid salt and was formed conventionally, this electrodialysis stack could operate over a very long period of time before the available acid salt packed in the cathode compartment was used up counteracting the base produced at the cathode. This construction allows an inexpensive electrodialysis stack to be assembled to operate over a long period of time without the need for expensive acid feeding apparatus.

As shown in FIG. 2, if both electrode compartments are

packed with a suitable acid salt, there may be periodic electrical reversal of the stack (preferably every half hour).

In such a case, the current source would be reversed so that the electrode 72 functioned as a cathode and the electrode 67 functioned as an anode. In this case the gaskets 50A would contain diluting cells, while the gaskets 50B contained concentrating cells, and the dilute stream would flow from the stack through the fluid flow apertures 71 while the concentrate stream flowed through the fluid flow apertures 70. In this case the electrode compartment containing the anode would receive water by electroendosmosis but there need be no fluid or acid loss if a standpipe 20 or 21 is provided having a suitable volume to accommodate the water carried into the anode compartment by electroendosmosis for a given period of time before electrical reversal. Upon electrical reversal, the electrode compartment which was functioning as an anode would now function as a cathode and excess water would be transferred back into the body of the stack with no loss of the acid salt in solution through the anion permeable membrane.

If it is desired to add acid to the concentrate stream, the stack may be constructed so that a concentrate cell is adjacent to the cathode. By using either a very strong acid or a more porous anion membrane adjacent to the cathode compartment, the acid may be permitted to diffuse into the adjacent concentrating cell.

While a given construction of an electrodialysis stack is shown having parallel flow through it, this invention is not limited to any particular stack construction. It may be used in any electrodialysis stack utilizing series flow, parallel flow or any combination thereof. This invention may be used in stacks which are built up as shown in this application, or it may be used in connection with circular or other stack construction.

What is claimed is:

The process of dispensing anions into the concentrating stream of an electrodialysis stack comprising the steps of:

- 40 (a) maintaining in a cathode compartment a solid material, comprising acid anions selected from solid acids and acid salts, in substantial equilibrium with a saturated aqueous solution of said solid material and
- 45 (b) diffusing said anions under electrical potential through an anion selective permeable membrane into an adjacent concentrating stream in an electrodialysis stack, whereby said solid material is depleted in the operation of said stack.
